UNITED STATES PATENT OFFICE.

EDWARD TRIMBLE, OF NEAR ST. JOSEPH, MISSOURI.

MARGINAL CHECK-CUTTER.

1,305,417.

Specification of Letters Patent.

Patented June 3, 1919.

Application filed April 9, 1917. Serial No. 160,749.

To all whom it may concern:

Be it known that I, EDWARD TRIMBLE, a citizen of the United States, residing near St. Joseph, in the county of Andrew and State of Missouri, have invented certain new and useful Improvements in Marginal Check-Cutters, of which the following is a specification, reference being had therein to the accompanying drawing.

10 My invention relates to improvements in that class of marginal cutters, which are used for cutting the margins of bank checks, express and postal money orders, and the like, which carry on their faces what are 15 commonly known as money margins.

The objects of my improvements are, to provide a simple, substantial, durable and efficient cutter of this class, which is detachably attached to the cover of a block of such 20 checks, and which can be folded in said block of checks, for enabling the user of the cutter and checks, to insert the same in his pocket. This provides a check cutter which is always at hand, ready for instant 25 use, and safeguards the same against misplacement or loss. Further objects are, to so construct the cutter and to so arrange the money margins, that checks for all of the various amounts, ranging from a comparatively small sum, to a very large one, are 30 practically safeguarded against having the amounts of said checks raised.

I attain these objects by the devices illustrated in the accompanying drawings, in 35 which:—

Figure 1 is a top plan of the cutter and of a block of checks, with the cutter in position for cutting the top margin of the upper one of said block of checks. Fig. 2 is a view 40 similar to Fig. 1, showing the cutter in position for cutting an end margin. Fig. 3 is a vertical section, on the line X X, seen in Fig. 2, looking toward the left. Fig. 4 is a vertical section of the cutter, on the line Y Y, seen 45 in Fig. 2.

Referring to Figs. 1 and 3, clamp bar 1 is provided with clamp hooks 2, formed on the ends thereof. Said hooks are slid onto the longitudinal edges of cover 3 for detachably 50 holding said clamp bar in place. Block of checks 4 has stubs 4' formed with said checks in the usual manner. Said checks have the longitudinal money margin 5 formed along the upper edges thereof and transverse margins 5' formed thereon. Said money mar-

gins are subdivided by the division lines 5''. Said block of checks is detachably connected with cover 3, by inserting the bottom one of checks 4 and its attached stub, into pocket 3', (see Fig. 3,) said pocket being 60 formed with said cover in the usual manner.

Referring to Fig. 1, the slide carrying rod 6 is formed with clamp bar 1, at a right angle thereto. Said rod has slide 7 mounted thereon. The free extremity of said rod has 65 enlarged portion 7' formed thereon, for holding said slide against detachment from said rod.

One end of the cutter carrying bar 8 is loosely connected with the slide by pivot 8'. 70 The free end of said bar has the inclined cutting edge 8'' formed thereon.

Cutting plate 9 has the slot 9' formed therethrough and is slidably secured on said cutter carrying bar by the headed stud 10, 75 passed through said slot and secured in said bar.

Said cutting plate has the longitudinal cutting edges 9^a and 9^b and the inclined transverse cutting edges 9^c and 9^d formed 80 thereon.

Checks 4 and back 3 are preferably formed of flexible material, for permitting the same to be folded on the dash and dot line Z Z.

In operation, with the parts of the cutter 85 in the position seen in Fig. 1, the operator of said cutter with one hand firmly presses bar 8 and plate 9 downward upon checks 4. While so doing he grasps the free transverse edge of the upper one of said checks, and 90 draws the same upward to practically a right angle to cutting edge 9^c, and continues drawing said check upward, thereby cutting the same against the full length of said cutting edge. Said operator then similarly 95 raises said check, longitudinally and cuts the same along the edge 9^a of plate 10 and the lower edge of the bar 8 and stops at the left edge of the first column of the transverse money margin 5'. He then swings bar 8 on 100 pivot 8' from the position seen in Fig. 1, to the position seen in Fig. 2, and slidably moves plate 9 to the position shown. Said operator then cuts said check along the right edge of bar 8 and edges 9^d and 9^b. This 105 severs the entire check 4 from stub 4', leaving the desired money designations on the margins of both.

The back surface of the longitudinal money margin 5 may be gummed for en- 110

abling the operator to double and adhere the severed portion of the same onto the back of stub 4', to prevent the same from being separated from said stub.

5 Stub 4' is turned over toward the left dis- closing the check, next beneath, after which the previously described operations are repeated. In each operation the inclined edges 9^e and 9^d are set to cut on such division lines 5" as the various amounts of 10 different checks may require.

15 While the money designations in the longitudinal money margin 5 designate amounts ranging from five dollars to ninety- five dollars and the designations in the transverse money margin 5', indicate from one hundred to thirty hundred dollars, it is evident that various different subdivisions 20 of said margins for indicating different amounts than the ones shown could be made, and that bar 8 and plate 9 could be differently shaped, to coördinate therewith, without departing from the spirit of my invention, which I reserve the right to do.

25 Referring to Fig. 2, plate 9 is slid upward, until its upper end is against slide 7, after which back 3 and the therewith connected checks 4 are folded on the dash and dot line Z Z.

30 The check book, thus folded, incloses all of the described check cutter, except slide bar 6 and the outer portion of slide 7. This places the check book and the therein inclosed parts of the cutter in small and compact form for insertion in the pocket of the 35 user.

When all of checks 4 are used, as previously described clamp bar 1 and the therewith formed hooks 2, are slid from cover 3 40 and another block of checks is connected with the latter, as previously described, and

said clamp bar and hooks are returned to the position shown.

Having fully described my invention, what I claim as new and desire to secure by Letters Patent is:—

A marginal check cutter, comprising, a clamp bar having clamp hooks formed on the ends thereof for clamping said bar transversely on one end of the cover of a check book having blank sheets provided with longitudinal and transverse money designating margins; a slide carrying rod formed integrally with one end of said clamp bar at a right angle thereto said rod being outside of and parallel with one of the longitudinal edges of said book; a slide mounted on said rod; slide holding means formed on the free extremity of said rod for holding said slide thereon against detachment therefrom; a cutting bar having one of its ends pivotally connected with said slide for permitting said cutting bar to be swung in a horizontal plane; and a cutting plate slidably secured on said cutting bar one edge of said plate being against the adjacent edge of said cutting bar and its opposite edge extended beyond said bar for adapting said extended edge portion to cover a transverse money designating margin of a check, the edges of said cutting bar and of said plate being adapted to cut said longitudinal and transverse money designating margins from a check when the latter is drawn thereagainst.

70 In testimony whereof I affix my signature in the presence of two witnesses.

EDWARD TRIMBLE.
